UNITED STATES PATENT OFFICE.

GEORGE A. CLARK, OF SEATTLE, WASHINGTON.

CAST-OFF FOR SUSPENDERS.

Application filed August 31, 1922. Serial No. 585,396.

To all whom it may concern:

Be it known that I, GEORGE A. CLARK, a citizen of the United States of America, and resident of the city of Seattle, in the county of King and State of Washington, have invented certain new and useful Improvements in Cast-Offs for Suspenders, of which the following is a specification.

My invention relates to cast-offs such as are used for suspenders and has for its object to make an improved cast-off which is not likely to become unintentionally disengaged and one which will minimize wearing of the web or material of the strap by the action of disengaging it.

Other objects of my invention may be determined from a study of the description following hereafter and the claims which terminate the specification.

20 The features of my invention which I believe to be new and upon which I desire to obtain a patent will be hereinafter set forth and then specifically defined by the claims.

25 The accompanying drawings show my invention in a preferred form of construction.

Figure 1 shows a front view of the cast-off with adjacent portions of both the strap and the cord.

30 Figure 2 is a central longitudinal section taken through that part of the article shown in Figure 1.

Figure 3 is an edge view seen from above of the upper or bar member of the cast-off.

35 There are two parts to this cast-off, one being the strap member 1 designed for attachment thereto of the web or strap of the suspender, and the other the cord member 2 which is adapted to be secured upon the cord or equivalent member 5 which is secured to the buttons of the trousers. The upper or strap member 1 is in the form of a plate having a longitudinal slot 10 therein of such size as to receive therein the web 4 of a suspender. This forms an upper bar 40 12 and a lower bar 11. Depending centrally from the lower bar is an ear 13 which carries a forwardly projecting pin 3. This pin is provided with a head 30 which in my improved form of construction is offset relative to the pin 3 so that the lower edge of the head 30 is flush with the lower surface of the pin. While this feature of construction is not essential in connection with certain features of my invention, it is, however, 45 a desirable one which I prefer to use.

The cord member 2 is formed of a piece of

sheet metal bent upon itself to form an eye 23 which receives the cord 5 or other equivalent member which is adapted to be secured to the buttons of the trousers. It has two 60 arms 20 and 21 extending from the eye in substantially parallel relation with each other but normally slightly separated toward their outer ends. These should preferably contact close to the eye. One or both of these members should have sufficient resilience that they may be pressed closer together and will, when unrestrained, be separated at their ends. Each of these arms is provided with a slot adapted in its lower 70 end to pass the head 30 of the pin and reduced in width at its upper end so as to receive the shank of the pin 3 but not to pass the head. Such a slot in the preferred form of construction is shown, consisting of the 75 key hole slot 22. These slots in the two arms register with each other in the completed article.

The face of the outer or forward arm 21 is provided with a forward projection or 80 projections located so as to be engaged by the side projecting wings of the head 30 so that as the pin is given relative movement lengthwise of the slot the outer arm 21 will be forced closer to the rear arm 20. In the 85 preferred construction this result is secured by forming a slight outwardly projecting transverse crimp or corrugation 24 in the sides of the outer arm 21, which by its engagement with the side wings of the head 90 30 prevent unintentional movement of the pin downward in the slots and therefore prevent unintentional separation of the parts.

The ear 13 of the strap member 1 is given a slight rearward inclination towards its 95 lower end. The object of this is to place the plane of the cord member 2 at such an inclination that as it is moved upwardly it will not gouge into the bend in the web 4 and thus cause wear. For the same reason the inner arm 20 is given a slight outward bend which may be accentuated at its tip, as shown at 25. Should the upper end of this arm engage the web, this rounded outwardly bent tip will cause it to slide over the web without catching or gouging thereinto. The curvature of the main body of the arm will cause its upper end to be deflected out as it moves upward, thus decreasing the possibility of engaging the web. 100 105 110

For the same purpose, namely, the offsetting of the cord member 2 relative to

the web, I prefer to have the lower bar 11 of the strap member bent so that its central portion is offset forwardly of the bar 12, as is clearly indicated in Figures 2 and 3.

- 5 A cast-off of this construction will not become accidentally separated by any ordinary occurrence. Slack between the two parts and a tendency of the lower to lift will not cause it to be disengaged from the pin. The 10 resiliency of the arms 20 and 21 and the fact that the humps 24 are below the head 30 will furnish frictional resistance to forcing the head of the pin over the humps 24 and this will be enough to cause the upper member 15 of the cast-off to be lifted and thus prevent separation of the two parts. At the same time separation may easily be secured by holding the upper or strap member 1 while lifting the lower or cord member 2.
- 20 The arms 20 and 21 being close together near the eye 23, or in that part which contains the eye 22 of the keyhole slot, make easy the placing of the eye member 2 over the pin 3. As the eye member 2 is drawn 25 down upon the pin the resiliency of the arms 20 and 21 permit giving enough to permit the head of the pin to pass over the humps 24 and the same resiliency prevents downward relative movement of the pin 3 30 from any ordinary cause until this is intentionally caused by engagement of the two parts. Furthermore, by offsetting the head 30 of the pin upwards so that its lower edge is flush with the shank, the head may be 35 drawn easily over the lower edge of the slot 22 without catching.

What I claim as my invention is:

1. A cast-off for suspenders comprising a member having a pin provided with a head and a member complementary thereto and having two resiliently separated arms each provided with a keyhole slot for the reception of said pin, one of said arms having a projection from its general plane and located between the small and the large end of the slot, and engageable by the head of the pin when the latter is moved from the small end towards the large end of the slot.
2. A cast-off for suspenders comprising two complementary parts one having a projecting pin provided with a head and the

other having two resiliently separated arms provided with like and registering keyhole slots for the reception of said pin, one of said arms having face projections engageable with the head of the pin to yieldingly resist movement of the pin between the two ends of the slot. 55

3. A cast-off for suspenders comprising a plate longitudinally slotted to receive the suspender web and having an ear depending centrally from the lower bar thus formed, said lower bar being centrally offset forwardly and the ear being slightly inclined rearwardly, a pin projecting forwardly from said ear and having a head and a complementary member having two resiliently separated arms provided with registering keyhole slots adapted to receive said pin, one of said arms having face projections forwardly 65 of its general plane adapted to engage the inner face of the head to prevent unintentional removal from the pin. 70

4. A cast-off for suspenders comprising a plate longitudinally slotted to receive the suspender web and having an ear depending centrally from the lower bar thus formed, said lower bar being centrally offset forwardly and the ear being slightly inclined rearwardly, a pin projecting forwardly 80 from said ear and having a head and a complementary member having two resiliently separated arms provided with registering keyhole slots adapted to receive said pin, one of said arms having its sides crimped to 85 form forwardly projecting ribs extending transversely and positioned between the large and small ends of the slot therein, and adapted to engage the head of the pin to prevent unintentional removal of said arms 90 from the pin. 95

5. A suspender cast-off having two complementary members one provided with a projecting pin having a head offset to have its lower edge flush with the lower edge of the pin proper, the other member having a slot for the reception of said pin enlarged in its lower part to pass the pin head.

Signed at Seattle, King County, Washington, this 25th day of August 1922.

GEORGE A. CLARK.
